US00D821034S

(12) **United States Design Patent** (10) Patent No.: **US D821,034 S**
 Langdon et al. (45) Date of Patent: ** Jun. 19, 2018

(54) **COSMETIC COMPACT**

(71) Applicants: **Megan Rene Langdon**, Los Angeles, CA (US); **Armando Villarreal**, Los Angeles, CA (US)

(72) Inventors: **Megan Rene Langdon**, Los Angeles, CA (US); **Armando Villarreal**, Los Angeles, CA (US)

(73) Assignee: **HCT GROUP HOLDINGS LIMITED**, Hong Kong (HK)

(**) Term: **15 Years**

(21) Appl. No.: **29/558,271**

(22) Filed: **Mar. 16, 2016**

(51) LOC (11) Cl. **28-03**

(52) U.S. Cl. USPC **D28/83**

(58) **Field of Classification Search**

USPC D28/76-81, 82-83, 85-89, 84
 CPC A45D 40/22-40/24; A45D 33/00; A45D
 33/003; A45D 33/006; A45D 33/04;
 A45D 33/22; A45D 33/24

CLAIM

The ornamental design for a cosmetic compact, as shown and described.

DESCRIPTION

FIG. 1 is a perspective view of a first embodiment of a cosmetic compact with the lid open;

FIG. 2 is a left side view of the first embodiment of a cosmetic compact with the lid open;
FIG. 3 is a right side view of the first embodiment of a cosmetic compact with the lid open;
FIG. 4 is a front view of the first embodiment of a cosmetic compact with the lid open;
FIG. 5 is a rear view of the first embodiment of a cosmetic compact with the lid open;
FIG. 6 is a top view of the first embodiment of a cosmetic compact with the lid open;
FIG. 7 is a bottom view of the first embodiment of a cosmetic compact with the lid open;
FIG. 8 is a perspective view of a first embodiment of a cosmetic compact with the lid closed;
FIG. 9 is a left side view of the first embodiment of a cosmetic compact with the lid closed;
FIG. 10 is a right side view of the first embodiment of a cosmetic compact with the lid closed;
FIG. 11 is a front view of the first embodiment of a cosmetic compact with the lid closed;
FIG. 12 is a rear view of the first embodiment of a cosmetic compact with the lid closed;
FIG. 13 is a top view of the first embodiment of a cosmetic compact with the lid closed;
FIG. 14 is a bottom view of the first embodiment of a cosmetic compact with the lid closed;
FIG. 15 is a perspective view of a second embodiment of a cosmetic compact with the lid open;
FIG. 16 is a left side view of the second embodiment of a cosmetic compact with the lid open;
FIG. 17 is a right side view of the second embodiment of a cosmetic compact with the lid open;
FIG. 18 is a front view of the second embodiment of a cosmetic compact with the lid open;
FIG. 19 is a rear view of the second embodiment of a cosmetic compact with the lid open;
FIG. 20 is a top view of the second embodiment of a cosmetic compact with the lid open;
FIG. 21 is a bottom view of the second embodiment of a cosmetic compact with the lid open;
FIG. 22 is a perspective view of a second embodiment of a cosmetic compact with the lid closed;
FIG. 23 is a left side view of the second embodiment of a cosmetic compact with the lid closed;
FIG. 24 is a right side view of the second embodiment of a cosmetic compact with the lid closed;

FIG. 25 is a front view of the second embodiment of a cosmetic compact with the lid closed;
FIG. 26 is a rear view of the second embodiment of a cosmetic compact with the lid closed;
FIG. 27 is a top view of the second embodiment of a cosmetic compact with the lid closed;
FIG. 28 is a bottom view of the second embodiment of a cosmetic compact with the lid closed;
FIG. 29 is a perspective view of a third embodiment of a cosmetic compact with the lid open;
FIG. 30 is a left side view of the third embodiment of a cosmetic compact with the lid open;
FIG. 31 is a right side view of the third embodiment of a cosmetic compact with the lid open;
FIG. 32 is a front view of the third embodiment of a cosmetic compact with the lid open;
FIG. 33 is a rear view of the third embodiment of a cosmetic compact with the lid open;
FIG. 34 is a top view of the third embodiment of a cosmetic compact with the lid open;
FIG. 35 is a bottom view of the third embodiment of a cosmetic compact with the lid open;
FIG. 36 is a perspective view of a third embodiment of a cosmetic compact with the lid closed;
FIG. 37 is a left side view of the third embodiment of a cosmetic compact with the lid closed;
FIG. 38 is a right side view of the third embodiment of a cosmetic compact with the lid closed;
FIG. 39 is a front view of the third embodiment of a cosmetic compact with the lid closed;
FIG. 40 is a rear view of the third embodiment of a cosmetic compact with the lid closed;
FIG. 41 is a top view of the third embodiment of a cosmetic compact with the lid closed; and,
FIG. 42 is a bottom view of the third embodiment of a cosmetic compact with the lid closed.
The evenly spaced broken lines which illustrate the bottom and interior of the cosmetic compact form no part of the claimed design. The cosmetic compact is shown with a symbolic break in its length. The dash-dot-dash broken lines illustrate the break lines and form no part of the claimed design. The appearance of any portion of the cosmetic compact between the break lines forms no part of the claimed design.
